UNITED STATES PATENT OFFICE.

JESSE A. CRANDALL, OF BROOKLYN, NEW YORK.

BUILDING-BLOCKS.

SPECIFICATION forming part of Letters Patent No. 270,206, dated January 9, 1883.

Application filed November 25, 1882. (No model.)

To all whom it may concern:

Be it known that I, JESSE A. CRANDALL, of Brooklyn, in the county of Kings and State of New York, have invented an Improved Building-Block, of which the following is a specification.

Figure 1 represents a plan view of four of my improved building-blocks placed together; Fig. 2, a plan view of the same four blocks, 10 showing them placed in a different position; Fig. 3, an elevation showing three of said blocks placed in another position. Fig. 4 is a side view of a representation of a light-house produced from my new blocks. Fig. 5 is a 15 top view of the circular part of the light-house; Fig. 6, a top view of the uppermost portion of said light-house; Fig. 7, a side view of one of the blocks used in said uppermost portion, and Fig. 8 a perspective view of a cube produced 20 from four of my improved blocks.

This invention relates to a new building-block for children; and it consists in making said building-block mainly of triangular form, so that such a block can be utilized in producing a great variety of structures; also in beveling two of the corners of each triangular block, all as hereinafter more fully described.

In the accompanying drawings, with special reference to Fig. 1, the letters A, B, C, and D represent four of my building-blocks. Each of these blocks has substantially triangular faces, as shown in Figs. 1 and 2, and quadrangular ends, as shown in Fig. 2; but one part 35 of my invention consists, also, in beveling off two of the corners, a and b, of each of said blocks. The blocks are of suitable size and thickness, and Fig. 4 shows a structure built up of series of these blocks, each series containing four, the series in Fig. 4 being marked 1, 2, 3, 4, 5, 6, 7, 8, 9, and 10, respectively. It will be seen from that figure that the blocks 40 1, 2, 4, 6, and 8 are of lesser thickness than the blocks 3, 5, 7, and 9, and that their lengths 45 or lines of base are also varying.

The structure built up of the triangular blocks may be smaller when the blocks are arranged as in Fig. 1—that is, with the bases of the triangles on the outer side; or the blocks 50 may be placed, as in Fig. 2, with the bases of

the triangles on the inner side, and it will be clearly seen that a larger structure can be built up from a given number of blocks when the blocks are placed as in Fig. 2 than there could be made from them as placed in Fig. 1. 55 By beveling the edges b a the structure built up as in Fig. 2 is made the firmer, because there are short contact-faces for the blocks, which would not exist if complete triangular forms were selected; and, moreover, in building up a structure by arranging the blocks as in Fig. 1 the real outline will be substantially octagonal and give room for exercising the ingenuity of the child, in requiring it to match the abutting faces a b of the several blocks 60 that pertain to each series, said faces being provided with letters of the alphabet, representations of faces, or other decorations that may be completed by properly matching the several blocks. Another advantage obtained 65 from the use of these blocks is that their faces and edges may bear varying ornaments, which will produce different effects, according to the manner in which the blocks are arranged. Thus, for example, the four principal exposed 70 faces resulting from the arrangement shown in Fig. 1 may exhibit letters, representations of men, and inscriptions, whereas the eight exposed faces resulting from the arrangement shown in Fig. 2 may represent legends or 75 decorations of an entirely different character, and may, moreover, require the proper matching of the blocks. The blocks may also be arranged into representations of houses, as in Fig. 3, in which case their exposed ends will 80 be utilized to aid in completing the effect of the structure to be represented, and thus the said blocks can be a source of infinite amusement and instruction, more so than the ordinary cubical blocks now usually employed. 85 The said blocks can also be arranged, as in Fig. 8, to take the place of the ordinary letter-blocks.

The blocks E E (shown in Fig. 5) can be added, if desired, to the collection of blocks 90 A B C D, to produce such effects as that shown in Fig. 4, and likewise the blocks F F. (Shown in Figs. 6 and 7.)

I claim—

1. The building-blocks A B C D, con- 100

structed with triangular faces, quadrangular ends, and with ornamentations thereon for combined use, substantially as herein shown and described.

2. The building-blocks A B C D, made with triangular faces, quadrangular ends, and beveled corners *a b*, substantially as herein shown and described.

This specification of my invention signed this 23d day of November, 1882.

JESSE A. CRANDALL.
